FIG. 1

FIG. 2

FIG. 3

FIG. 4

FIGURE 1 is an elevational view of the top of a hitch pin showing my new design.

FIGURE 2 is an elevational view of the side of the hitch pin, or stated differently, the hitch pin as it appears when it is rotated about its longitudinal axis by an amount of 90° from the position illustrated in FIGURE 1.

FIGURE 3 is an elevational view of one end of the hitch pin.

FIGURE 4 is an elevational view of the other end of the hitch pin.

I claim:

The ornamental design for a hitch pin, substantially as shown.
